Jacob HArnbruster

United States Patent Office.

JACOB H. ARMBRUSTER, OF PHILADELPHIA, PENNSYLVANIA.

Design No. 2,929, dated February 11, 1868.

DESIGN FOR A TRADE-MARK.

The Schedule referred to in these Letters Patent and making part of the same.

TO ALL WHOM IT MAY CONCERN:

Be it known that I, JACOB H. ARMBRUSTER, of the city and county of Philadelphia, and State of Pennsylvania, have invented a new Design for Trade-Mark; and I do hereby declare the following to be a clear and exact description of the nature thereof, sufficient to enable others skilled in the art to which my invention appertains to fully understand and use the same, reference being had to the accompanying drawings, making part of this specification, in which the figures represent the design illustrating my invention, which I intend to apply for any purposes of the business in which I am engaged.

In general description my design consists of a capital letter, A, whose legs, *a*, rest on feet, *b*. The cross-piece *c* may have its lower side formed with curves or arches, *d*, which are united, and have the point of union terminated in a small ball or circle, *e*. An arm, *f*, projects from each side of the upper end of the letter A. This letter may be cross-lined, or entirely filled in, and its formation is then complete. From the cross-piece *c* of the letter, there arises a bow-gun, B, whose butt *g* rests thereon, and its stock passes vertically past the upper junction of the legs of the letter A, and extends some distance above the top of said letter. The bow *h* is bent, and its cord *i* drawn and held in the nick or slit, above the trigger, ready to be discharged. In the space below the cross-piece *c*, I place the letters J. H. The cross-piece of the letter H is connected to the letter J. The three letters form the initials J. H. A.

The design may be cut, stamped, or printed, light or heavy, as shown in the drawings, and of size to suit its application.

Having thus described my invention, what I claim as new, and desire to secure by Letters Patent, is—
The design for trade-mark, substantially as represented and described.

To the above I have signed my name, this twentieth day of January, 1868.

JACOB H. ARMBRUSTER.
